UNITED STATES PATENT OFFICE.

GEORGE M. HOLBROOK, OF CHICAGO, ILLINOIS, ASSIGNOR TO ARMOUR AND COMPANY, OF CHICAGO, ILLINOIS, A CORPORATION OF ILLINOIS.

PROCESS OF REFINING OIL.

1,169,155.

Specification of Letters Patent.

Patented Jan. 25, 1916.

No Drawing.

Application filed November 15, 1915. Serial No. 61,503.

To all whom it may concern:

Be it known that I, GEORGE M. HOLBROOK, a citizen of the United States, residing at Chicago, in the county of Cook and State of Illinois, have invented certain new and useful Improvements in Processes of Refining Oil, of which the following is a specification.

This invention relates to improvements and features of novelty in the processes of refining oil, and more particularly relates to the purifying of crude cotton-seed oil for various industrial and food purposes, whereby to procure desirable qualities of refined oil of higher grade as to color with less manipulation and with a smaller refining loss than has been possible by other known methods.

It has heretofore been proposed, as for example, in United States Patent No. 1,007,642, granted October 31, 1911, to refine crude cotton-seed oil by first treating the oil with an aqueous solution of a water-soluble alkaline-silicate, such for example, as sodium tetrasilicate, until the acidity of the oil is approximately overcome and then subjecting it to the action of an alkaline hydroxid, such for example, as sodium hydroxid, which brings about a precipitation of the soap-stock. Such a method as this has certain objectionable features, because sodium silicate seems to have a chemical effect upon the coloring matter in the crude oil which renders it more or less immune to further decolorization during the secondary treatment.

The main object of the present invention is the provision of a method or process which will permit the purification of crude cotton-seed oil in such a way as to result in an oil of the desired color and with a minimum of refining loss. In order to do this, in view of the discovery of the detrimental action of the sodium silicate referred to, it is necessary to avoid the well-known process specified above of treating the oil first with sodium silicate and then with sodium hydroxid.

In accordance with the principles of the present invention, the crude cotton-seed oil is treated initially with sodium hydroxid and then with a mixture of sodium hydroxid and sodium silicate, this process having the advantage over the others that the neutralizing of the free fatty acids out of

contact with the silicate prevents the setting of the color, which, if it occurred, would be difficult or impossible to remove under further treatment. Under this process, a portion of the color is removed during the first step and another portion during the second step, the sodium hydroxid constituting the vital or real refining agent, the silicate being used as a compacting or condensing agent for the foots or soap-stock, to reduce the amount of neutral oil in such foots, or, stated differently, to diminish the refining shrinkage.

The manner of performing this improved process, the percentages of ingredients employed, the temperatures reached, etc., depend upon the nature of the crude oil to be purified and the color to be attained in the refined product. We may assume, however, a typical case in which the crude cotton-seed oil has 1% of free fatty acids. To this oil is added 1% by weight of a suitable solution of caustic alkali, such as sodium hydroxid solution, 18 Baumé, or its equivalent in caustic strength. Sufficient agitation is effected to complete the contact of all particles of the oil with the caustic alkali to thoroughly neutralize the free fatty acids, which are always present in crude cotton-seed oil. Then a mixture of an aqueous solution of sodium hydroxid and an aqueous solution of sodium silicate composed of 3% by weight of the oil treated, 18 Baumé, sodium hydroxid or its equivalent and $\frac{1}{4}$ of 1% by weight of the oil treated of sodium silicate of commercial grade, namely 44 Baumé, is added. After agitation for about 15 minutes at an initial temperature of about 80° Fahrenheit, the temperature of the oil and its contained solutions is slowly raised to about 115° Fahrenheit, whereupon the soap-stock will separate readily and completely from the refined oil, which will be of much clearer and lighter color than in the crude state. In carrying out this process, the original caustic soda solution neutralizes all, or practically all of the fatty acids, a slight excess of the caustic preferably being used for this purpose of assuring complete neutralization, and it also precipitates a portion of the coloring matter and other impurities. The soap-stock is not permitted to settle at this time, as it would ordinarily, until the silicate is introduced, which appar-

ently, has the property of combining with the products of the previous refinement and thereby the soap-stock thus formed settles in a compact, glassy condition, which more readily expresses the oil and forms a soap-stock which separates from the oil easily by reason of its increased specific gravity. The agitation is continued after the silicate is added until the proper temperature is reached for the separation of the soap-stock in order to assure a complete intermixture of the ingredients. Stated somewhat differently, by carrying out the process in the two steps, as indicated, the final soap-stock or foots is precipitated in a compact, plastic, or glassy condition which tends to liberate part of the oil which might otherwise be held in suspension mechanically.

As has been indicated above, the free fatty acids of the oil are neutralized before the silicate is used, as the employment of such silicate in any considerable proportion or by itself in contact with the crude cotton-seed oil containing such free fatty acids has a deleterious effect upon the color, which necessitates the use of a larger percentage of sodium hydroxid in the subsequent treatment in order to produce a refined oil of the desired color or it may be impossible to overcome the prejudicial effect on the coloring material. By this process, as has been explained, such injurious effect of the silicate on the coloring, is prevented by first neutralizing the free fatty acids with the sodium hydroxid.

To those skilled in this art it will be clear that various minor changes may be made in the process outlined herein without departure from the substance of the invention or the sacrifice of any of its advantages.

In the particular process outlined above the refining or purifying of crude cotton-seed oil has been referred to, but it is to be understood that the process is susceptible of satisfactory use in connection with many vegetable and animal oils, and is not limited to the cotton-seed oil mentioned.

I claim:

1. The process of refining crude cotton-seed oil and the like, consisting in substantially neutralizing the free fatty acids of

the oil by caustic alkali, then treating the oil with a mixture of caustic alkali and a silicate, and separating the refined oil from the soap-stock formed, substantially as described.

2. The process of refining crude cotton-seed oil and the like, consisting in substantially neutralizing the free fatty acids of the oil by an aqueous solution of caustic alkali, then treating the oil with a mixture of an aqueous solution of caustic alkali and an aqueous solution of a silicate, and separating the refined oil from the soap-stock formed, substantially as described.

3. The process of refining crude cotton-seed oil and the like, consisting in substantially neutralizing the free fatty acids of the oil out of contact with a silicate, then producing compacted or condensed soap-stock or foots in the presence of a silicate, and separating the refined oil from such soap-stock or foots, substantially as described.

4. The process of refining crude cotton-seed oil and the like, consisting in substantially neutralizing the free fatty acids of the oil by a sodium hydroxid solution, then subjecting the oil to a mixture of an aqueous solution of sodium hydroxid and an aqueous solution of sodium silicate, and separating the refined oil from the soap-stock or foots produced, substantially as described.

5. The process of refining crude cotton-seed oil and the like having approximately 1% of free fatty acids, consisting in adding to the crude oil approximately 1% by weight of a sodium hydroxid solution, 18 Baumé, and agitating the same until the free fatty acids are substantially neutralized, then adding a mixture of approximately 3% by weight of the oil treated of an aqueous solution of sodium hydroxid, 18 Baumé, and approximately $\frac{1}{4}$ of 1% by weight of the oil treated of an aqueous solution of sodium silicate, 44 Baumé, agitating the mixture, and slowly raising the temperature to approximately 115° Fahrenheit, and then separating the refined oil from the soap-stock produced, substantially as described.

GEORGE M. HOLBROOK.
